UNITED STATES PATENT OFFICE.

JOHN T. McCRAW, OF AYLESWORTH, OKLAHOMA.

CATTLE-GUARD.

1,275,060.

Specification of Letters Patent.

Patented Aug. 6, 1918.

Application filed November 17, 1917. Serial No. 202,584.

To all whom it may concern:

Be it known that I, JOHN T. McCRAW, a citizen of the United States, residing at Aylesworth, in the county of Marshall and 5 State of Oklahoma, have invented new and useful Improvements in Cattle-Guards, of which the following is a specification.

This invention relates to new and useful improvements in cattle guards and the principal object of the invention is to provide a 10 guard which will prevent the cattle passing while at the same time will not injure the cattle in any way.

Another object of the invention is the provision of inclined frames placed on each side and between the rails of the track and carrying transversely arranged rods on which are mounted a plurality of rollers spaced apart by washers so that an animal attempting to 20 pass over the frames will be caused to slip back to the starting point.

Another object of the invention is to provide fenders for the raised ends of the frames to protect the guard from injury by 25 hanging bars or the like on the train.

Another object of the invention is to provide a device of this character which is simple and durable in construction, reliable and efficient in operation and one which can be 30 manufactured and placed upon the market at a minimum cost.

The invention also consists in certain other features of construction and in the combination and arrangement of the several 35 parts, to be hereinafter fully described, illustrated in the accompanying drawings and specifically pointed out in the appended claims.

In describing my invention in detail, reference will be had to the accompanying 40 drawings wherein like characters denote like or corresponding parts throughout the several views, and in which:

Figure 1 is a plan view of the invention.

Fig. 2 is a longitudinal section.

Fig. 3 is an enlarged detail view showing the arrangement of rollers and washers.

In these figures A indicates the rails of the track and B the ties thereof while 1 indicates the parts of the guard located on each side of the track and 2 indicates that part located between the rails. Each part of the guard consists of a number of parallel bars 3 lying parallel to the rails and having 50 perforations therein to receive the bars or bolts 4. These bolts may be held in place by any suitable means, as shown they are each provided with a head on one end and the other end screw threaded to receive a nut. These bolts receive a plurality of rollers 5 which are spaced apart by the sleeves or washers 6. As will be seen the rollers on adjacent bolts are arranged in staggered formation so that a roller on one bolt is located between a pair of rollers on the adjacent bolts. The rollers and sleeves are of such dimensions as to permit the free movement of the rollers on the bolts, but I prefer to make the spaces between the parts 55 small so as to prevent an animal's foot passing between the parts. As will be seen the three parts of the guard are similarly made though the middle part is much wider than the other parts, and said middle part is provided with a middle rod or bar 3' to support 60 the central parts of the bolts. The parallel bars 3 and 3' are connected together at their ends by the end bars 7 so as to form a complete frame of rectangular formation. The parts of the guard are supported in an inclined position on the ties of the track with their upper ends on a level with the top of the rails and their lower ends located below the top of the tie to which their ends are secured. To so support the parts of the guard 65 I provide legs 8 for the upper ends which have their upper ends secured to the frames and the lower ends suitably secured to the top of one of the ties, said legs being of such length as to support the upper end of 70 the guard level with the top of the rail. The lower end of the guard is secured to the side of the adjacent tie near the bottom side thereof and I may do this by connecting 75 straps 9 to said ends and securing said 95 straps to the tie by spikes or the like. The upper ends of the straps project above the end of the frame and have their upper ends bent at right angles and secured to the top of the tie. To secure this arrangement of 80 parts it may be necessary to replace the tie 100 next to the one to which the bottom of the guard is secured by a tie of less thickness as shown in the drawings at B'. To protect the guard from injury by hanging rods and 105 the like on a train I provide fenders 10 which may be formed of any suitable material, such as metal. These fenders have their upper ends suitably secured to the top of the guard, as by being bent around the 110 uppermost bolt, from which the rollers and washers are omitted, and the lower ends of

said fenders are spiked to the tie adjacent to the one to which the upper legs are secured.

It will be understood that the lower end of the guard is placed adjacent the crossing so that an animal passing over the crossing and starting to travel over the track would walk on the lower end and thus if it attempted to walk up the inclined surface of the guard the rollers and sleeves would rotate under its weight and thus cause the animal to slide back to the end of the guard. Thus the animal would be prevented from traveling along the track and at the same time the animal would not be injured by the guard. The sides of the guard are located sufficiently close to the rails of the track to prevent an animal's foot from passing between the said guard and the rails.

It is thought from the foregoing description that the advantages and novel features of my invention will be readily apparent.

I desire it to be understood that I may

make slight changes in the construction and in the combination and arrangement of the several parts, provided that such changes fall within the scope of the appended claim.

What I claim is:—

In a cattle guard, the combination of the rails and the ties, a frame, a plurality of transverse bars carried by said frame, upwardly extending legs secured to the top of one of the ties for supporting one end of the frame on a level with the rails, downwardly extending legs connected with the other end of the frame and having their upper ends connected with the top of another tie for supporting said lower end below the top of said tie, a shield covering the high end of the frame and having one end hinged on the uppermost bar and its other end connected with a tie located beyond said frame and a plurality of rollers on the remaining bars.

In testimony whereof I affix my signature.

JOHN T. McCRAW,

Copies of this patent may be obtained for five cents each, by addressing the "Commissioner of Patents, Washington, D. C."
